UNITED STATES PATENT OFFICE

GEORG STAUBER, OF BERLIN, GERMANY

ROTARY MECHANICAL APPARATUS

Application filed April 24, 1931, Serial No. 532,620, and in Germany January 23, 1931.

My invention relates in general to rotary machines, power engines and compressors of the type comprising a casing with an eccentrically disposed rotor adapted to revolve therein and equipped with vanes, flaps, valves or the like acting or adapted to confine working chambers or variable volume which, in a certain position, that is to say at the moment, of least volume during operation, are entirely filled or charged with a suitable liquid. The surfaces of the liquid tending to move outwards during the revolution of the rotor due to centrifugal action, act in machines of this type in the manner of piston surfaces, since the distance thereof from the axis of the rotor is variable and will considerably vary during each revolution due to and in accordance with the eccentric position of the rotor. Machines of this type are susceptible of various modifications depending upon whether they are intended for use as pumps, power engines or the like. The particular constructions hitherto devised, however, are either objectionable for certain concomitant disadvantages or incapable of performing the work they are designed and intended for, for the reason that the surfaces of the liquid do not remain intact during normal operations and during the regulation or controlling of the machine.

The main object of my invention is to obviate the defects of machines of the type referred to, and accordingly the invention also comprises certain constructional measures and modifications for the particular purpose of having the said liquid surfaces remain intact or smooth during the normal operation and also during regulation whereby a satisfactory efficiency grade will be secured. Other detailed features of the invention will be specifically described hereinafter and then pointed out in the claims.

The inventive idea involved is capable of expression in a variety of mechanical forms one of which, for the purpose of illustration and exemplification, is shown in the accompanying drawings forming a part of this specification, but it is to be understood that said drawings are intended for illustration or exemplification only and not for the purpose

of defining the limits of the invention, reference being had to the claims for this purpose.

In said drawings Figure 1 is a longitudinal vertical section of my improved machine;

Figure 2 is a view in cross section between points II—II of Figure 1;

Figure 3 is a sectional view between points III—III of Figure 1;

Figure 4 is another view in cross-section between points IV—IV of Figure 1;

Figure 5 is a view in cross-section of one of the working chambers, confined by radial ribs, at the moment of rotation, where the chamber shows about medium useful clearance.

Figure 5a is a similar sectional view of a modified chamber confined by tangential ribs instead of radial ribs;

Figure 6 is a sectional view similar to that illustrated in Figure 5, but showing the chamber at the moment of rotation, just prior to the point of its maximum useful clearance; and

Figure 7 is a diagram showing the necessary ratio between the stroke of the liquid and the eccentricity of the machine or rotor.

The machine shown in the drawings for purposes of exemplification is of the compressor type but can be also adapted for use as a power engine, since in the latter case it will be necessary only to supply the same either with an explosive fuel mixture and cause the latter to explode, or with compressed gases and allow the latter to expand in the engine, the constructional features of and the objects aimed at by the invention remaining the same in either case.

The machine shown in the drawings comprises a casing composed of three parts, viz., sections 1, 2 and 3, whereof the parts 1 and 2 constitute the side walls while part 3 is the main body of cylindrical form firmly connected with parts 1 and 2 by means of bolts 4 and 5 or in any other appropriate manner. Mounted in the end walls of the cylindrical casing are ball bearings 6, 7 and 8 for supporting shaft 9. It will be seen from Figures 1 to 4 that the said bearings are located eccentrically with relation to the centre line or axis of the cylindrical casing, the bearing

8 being a thrust bearing to prevent axial displacement of the shaft 9, the bearing 6 being secured in position by an annular cap 10 rigidly connected with the side wall 1 by means 5 of screw bolts 11 and 12 and the bearing 7 being secured in position by means of an annular member 13 firmly united with the side wall 2 by means of the bolts 14 and 15. The bearing 8 in turn is secured in position by 10 means of a cap 16 firmly attached to the member 13 by means of bolts 17 and 18, as will be clearly understood upon inspection of Figure 1.

Mounted on the two ends of the shaft 9 are 15 two bushings 19 and 20 of relatively soft metal such as brass or the like, fitted to revolve simultaneously with the shaft and serving as a means for securing a tight fit between the shaft and the end walls of the stationary casing. Intermediate between the two bushings 19 and 20 there is provided on the shaft a sleeve 21 elongated to fit in or fill the full length thereof between the bushings, and equipped with two annular flanges. 20 This flanged sleeve 21 may be made in one piece or may consist of two symmetrical parts or halves, as shown in the embodiment illustrated, and which are immovably connected with the shaft by means of keys 23 and 23^a in keyways 22 and 22^a, respectively. 25

A light-fitting annular member or ring 24 is inserted between the two flanges of the sleeve 21 and secured thereto by screws 25, 26, 27, 28 with counter-sunk heads, so that 30 the circumferential surfaces of the two flanges would lie flush with the outer periphery of the ring 24 but for radial or outwardly projecting ribs 29 integrally formed with the ring 24. In the embodiment shown 35 there are provided ten ribs 29 each enlarged and shaped at its outer or free end to form a longitudinal hole 30 for the reception of a rod or pin 31 on the projecting ends of which a flap 33 is disposed in end to end abutting 40 relation to the hole end of the rib 29, as will be readily seen in Figure 1, so that the flaps 33 will be connected in pivot with the ribs 29 in the manner of a hinge. 45

The outer ends of the flaps 33 are likewise 50 enlarged and shaped to form longitudinal holes or eyes for the reception of a rod or shaft 34 whereof the projecting free ends carry or are attached in pivot to shoes 35 displaceably mounted in a circular groove 36 of the bipartite revolving drum 37 and 37^a, as will be seen in Figure 2. The drum is composed of two parts on halves 37 and 37^a for the purpose of facilitating ready assemblage of the parts constituting the rotor, particularly the 55 insertion of the rods or shafts 34, and the diameter of the drum is dimensioned to allow the latter to freely rotate within the cylindrical main body 3 of the casing. 60

The drum necessarily must be locked with 65 the shaft 9 in order to rotate therewith. The

positive connection between the two parts, however, must be such as to allow of a certain relative movement between the same, in consideration of the eccentrical disposition of the inner running ring 24 relative to the drum 70 27 and 27^a. For this reason only one of the ten rods or shafts 34 is elongated to project with its extremities 38 into bores provided in the end walls of the drum, as will be seen in Figure 1. 75

As in the embodiment illustrated the ribs 29 are not connected with the shaft 9 except by the width of the running ring 24, and not in full length, it is advisable to interconnect the inner corners thereof by means of rings 56 and 57 as shown in Figure 1, so that the edges of the flaps can be better operated and trued-up and, on the other hand, the flaps will thus be prevented from shimmying during the operation of the machine. 80

Intermediate between each pair of adjacent ribs 29 there are provided two shorter ribs 32 in the embodiment shown in the drawings, for purposes which will be explained further below. Both the larger ribs 29 and the shorter ribs 32 are integrally connected with the running ring 24 and, therefore, all of the said parts are rigidly interconnected while the ten larger ribs 29 are further interconnected by the rings 56 and 57. Packing rings 58 and 59 are provided for the purpose of preventing the liquid from trickling into and through the interstices between the drums 37, 37^a, and the casing 1, 2, 3. 90

The inner side of the end wall 1 is shaped to form a tubular extension 53 and the other end wall 2 is similarly shaped to form a like extension 54, the two extensions being adapted to act as controlling cylinders. The end wall 1 is a hollow body, as will be seen in Figure 1, to afford or constitute an inlet passageway 39 which is in communication with the said tubular extension 53 and further with the rotor, an inlet port 40 being provided for the purpose in the circumferential wall of the extension 53. Similarly the controlling cylinder or extension 54 of the end wall 2 is provided with an outlet port 41 for communication with the outlet passageway 42 formed by the hollow end wall 2. 100

The outlet passageway 42 is equipped with means for drying the expelled gases and for separating liquid particles from the gases, said means comprising a rib 43 extending from the outlet port 41 down in slanting position for the length of half a circle around the shaft 9 or the sleeve 21, as will be seen in Figures 1 and 3, and further an annular partition 44 forming a sump 45 for the reception 110 of liquid separated off due to centrifugal action, a bore 46 being provided in the bottom of the sump for purposes of discharging said liquid, while another opening 47 in the lower part of the end wall 2 serves the purpose 115 120 125 130

of introducing fresh liquid into the spaces between the hinged flaps 33.

The operation of the machine shown in the drawings for purposes of exemplification, 5 is as follows:

The shaft 9 whereof the end 48 is provided with means for connection with a driving motor powered by electricity or any other source of power, acts to revolve the rotor structure comprising the parts 24 to 38, and to cause the desired or required amount of liquid such as oil or water, to be supplied to the individual chambers formed or confined by the ribs 29 and flaps 33. Due to centrifugal 10 action the liquid contained in the chambers between the said ribs 29 and flaps or vanes 33 will be forced against the inner circumferential surface of the drum 37, 37^a and will 15 form, when the rotor attains or runs with a sufficient speed, a circular layer thereon as diagrammatically shown in Figures 2 to 4.

Due to the eccentric arrangement of the running ring 24 relative to the periphery of the drum 37 the volume of each individual 20 working chamber formed by the ribs 29 and the hinged flaps 33 incessantly changes during rotation, the said working chambers having, in the embodiment shown, at the time when they occupy a position vertically below the shaft 9 the largest possible free volume, while the chamber diametrically opposite the lowermost chamber then will have a least possible free volume. Due to this change of the 25 free volume the liquid which at the lowermost position of the individual working chamber fills up only a part thereof, will be forced into the space between the radial ribs 29, when the working chamber moves into and reaches its topmost position, and will consequently displace the air from above the 30 surface of the liquid.

Figure 3 is a view in cross-section taken on a vertical line passing through the outlet 41 in Figure 1 and it will be seen from Figure 45 3 that the said outlet port is provided just at the place where the working chambers have a least possible volume. The opening edge 49 of the outlet port 41 is situated such- 50 wise that the desired or required final pressure of the compression will be just attained when the rib 29 passing the edge at a time commences to allow the content of the next following chamber or cell to flow out into 55 or through the outlet port 41. The relative situation of the opposite or closing edge 49^a of the outlet thus will be determined or defined by the cross-sectional area of the outlet 41 required for a satisfactory discharge of the liquid.

Figure 4 is a view in cross-section taken on a vertical line passing through the inlet port 40, in Figure 1. The inlet port 40 preferably extends circularly about the shaft 9 for such a length or so far as the volume of the working chamber gradually increases during revolu-

tion so that the suction produced by the gradual increase of the volume of the chamber during revolution can be fully utilized. At the point of the circumference where the working chamber has or attains a maximum 70 volume, that is to say, when the distance between the rotary axis and the surface of the liquid is at a maximum, the suction ceases and therefore, the closing edge 55 of the inlet port is located at this point, see Figure 4. 75

It will be understood from the herein before given description of the operation of the machine that the surfaces of the liquid in the several chambers act in the very same manner as the piston surfaces of power engines of the piston type. From this fact results the indispensable requirement that in order to secure unobjectionable operation of the machine, the liquid surfaces in the several working chambers must remain intact or smooth or, in other words, must not be allowed to splash or to be upset in any other way.

This requisite condition of the liquid in the chambers will be secured, in accordance with the present invention, by the fact, that the radial movements of the liquid surfaces always remain within the compass confined by the large radial ribs 29. The successful result of this fact will be readily understood on inspection of Figures 5 and 5a.

The inclined position of the surface 51 see Figure 5, does not produce or involve such small angles as the inclination of the surface 51^a in Figure 5a, showing tangential or non-radial ribs 29^a. If, as in Figure 5a the angles between or formed by the surface of the liquid and the surface of the ribs are too small, the surface of the liquid is inclined to break and back wash and be destroyed thereby. Consequently in the machine shown and described here the surfaces of the liquid in the chambers are prevented from reaching the circumferential zone in which the hinged flaps 33 are located and work.

A further feature of my invention relates to the provision of the short radial ribs 32 for purposes hereinafter explained with reference to Figure 6. If said ribs 32 were not provided either the surface 51 of the liquid would coincide with the line A and the clearance would be too large, or in other words, the efficiency grade of the machine would considerably decrease, or the surface of the liquid would coincide with the line B, that is to say, considerable portions of the liquid would escape through the outlet 41 together with the compressed air. The provision of the short ribs 32, however, entails a division or breaking of the inclination of the surface of the liquid at the end of the compression stroke, as will be understood upon inspection of Figure 6.

Another feature of the present invention resides in the particular choice of the ampli-

tude of the stroke of the surface of the liquid for the purpose of contributing to a permanently intact condition of the surface of the liquid. Experience teaches, and from the 5 hydraulic compressors of the type in question as hitherto constructed or suggested it will be seen, that the radial movements of the surface of the liquid entail the danger of liquid particles separating from the bulk of the 10 liquid and being smashed into foam, unless means are provided to obviate this defect.

Now, the invention is based in part upon the observation that the centrifugal acceleration acting upon every liquid particle, al- 15 ways must be greater than the radial stroke acceleration in order to prevent separation of such particles. In accordance therewith a particular relation between the stroke of the liquid level and the least distance of the 20 liquid level from the rotating axis is maintained and utilized according to the present invention, as will be understood from the diagram shown in Figure 7.

In Fig. 7 the character C denotes the axis 25 of the revolving shaft 9, M indicates the centre or longitudinal axis of the drum 37, 37a, S indicates the stroke of the liquid and R denotes the least distance of the surface of the liquid from the axis C of the shaft. 30 The aforesaid requirement that the centrifugal acceleration always be greater than the radial stroke acceleration, will be secured or complied with by the fact that R is always kept greater than

$$35 \quad \frac{s}{2}.$$

that is to say, one half of the stroke of the liquid is always kept smaller than the least or minimum distance of the surface of the 40 liquid from the axis C.

A still further feature of the present invention resides in the particular mode of regulation or control. In the embodiment of the invention shown for purposes of exemplification regulation is accomplished by changing or varying the charge of the individual working chambers by means of the conduit or bore 47 whereby the efficiency of the compressor will be changed or varied without 45 changing the speed. For as the liquid is tapped off from the conduit 47, the clearance in the working chambers increases so much that finally compression work will cease altogether and compressed air will not be produced or supplied anymore. This mode of regulating the machine affords the advantage of maintaining the individual surfaces of the liquid in the chambers unbroken.

The means provided, according to the in- 60 vention, for drying the expelled air in the passageway 42 comprises, as herein before explained, the ribs 43 extending in slanting position downwards from the outlet 4 for the length of half the periphery and the annular 65 partition 44. Liquid particles entrained by

the compressed air and escaping simultaneously therewith through the outlet port 41 into the passageway 42 will automatically separate from the compressed air due to centrifugal action and will be conveyed, with the aid of the rib 43, laterally and downwards into the sump 45 wherefrom they will be free to flow off through the bore 46. It will be seen that by the provision of the supply conduit 47 and the discharge conduit or bore 46 the operator will be enabled to renew the liquid in the machine continuously or intermittently during the operation of the machine.

I have herein shown and described in detail one practical construction of my present improvements, but it will be apparent that the invention is susceptible of embodiment in various other alternative forms and I, therefore, reserve the privilege of resorting to all such legitimate changes as may be fairly embodied within the spirit and scope of the invention as claimed.

What I claim is:

1. An engine or machine driven by or delivering gases comprising a cylindrical casing, a liquid charge therein, an eccentrically situated rotor with rotating flaps, the flaps being fitted with flat and radial ribs forming part of said rotating flaps, the surface of the liquid being adapted to oscillate between these ribs.

2. An engine or machine driven by or delivering gases comprising a cylindrical casing, a liquid charge therein, a rotor with rotating flaps, the latter being eccentrically arranged in relation to the middle axis of the casing and the eccentricity being smaller than the smallest distance between the liquid surface and the axis of the rotor.

3. An engine or machine driven by or delivering gases comprising a cylindrical casing, a liquid charge therein, an eccentrically situated rotor with rotating flaps, the rotor being provided with radial longer and shorter ribs, the latter being located in the spaces between the longer ribs.

4. An engine or machine driven by or delivering gases comprising a cylindrical casing, a liquid charge therein, an eccentrically situated rotor with rotating flaps, means being provided to vary the quantity of the liquid.

5. An engine or machine driven by or delivering gases comprising a cylindrical casing, a liquid charge therein, an eccentrically situated rotor with rotating flaps, conduits being arranged in the end walls of the casing to vary the quantity of the liquid.

6. An engine or machine driven by or delivering gases comprising a cylindrical casing, a liquid charge therein, an eccentrically situated rotor with rotating flaps, an outlet for the escaping gases or air being provided in the casing and means in the said outlet to

separate out the liquid particles entrained by the escaping gas.

7. In a machine or engine as claimed in claim 6 said means consisting of a slanting 5 rib extending downwards over half the circumference of the casing.

8. An engine or machine driven by or delivering gases comprising a cylindrical casing, a liquid charge therein, an eccentrically 10 situated rotor with rotating flaps, a stationary control cylinder, its middle axis being in alignment with the axis of the said rotor, the cylinder being divided in two parts, the one being provided with an opening for the 15 inlet and the other for the outlet of the gases.

9. An engine or machine driven by or delivering gases comprising a cylindrical casing, a liquid charge therein, an eccentrically 20 situated rotor with rotating flaps and radial ribs, the latter being stiffened by rings and the rings being fastened to the inner corners of the ribs.

In testimony whereof I affix my signature.
GEORG STAUBER.
